Application February 21, 1951, Serial No. 212,060

10 Claims. (Cl. 60—39.05)

1
This invention relates to a method of increasing the power output of continuous flow gas turbines.

The principal purpose of the invention is to provide novel methods and apparatus for producing power by the expansion through turbines of compressed gases heated by internal combustion, such novel methods and apparatus being especially adapted to reduce the cost per horsepower of the machines as compared to those of current types, when designed to obtain comparable thermal efficiency.

The typical internal combustion turbine comprises essentially three elements. The first element is a compressor, which takes in atmospheric air and forces it under substantial superatmospheric pressure into the second element, a combustion chamber or combustor in which the air meets fuel and combustion takes place, producing hot gases which pass to and through the third element, a turbine, in which expansion of the hot gases takes place with the generation of mechanical energy, part of which drives the compressor while the balance is available to drive a load.

The invention can be best appreciated and evaluated by considering first the operation of conventional apparatus now employed. As will be explained hereafter, the novel apparatus of the invention, for equal thermal efficiency produces approximately twice as much power as currently employed units of about the same size and operating under the same temperature and pressure conditions; this reduces the cost per horsepower to 40% less than that of comparable prior art units.

In a typical internal combustion turbine currently employed, an air flow rate of 90 pounds per second is used to produce 6,140 horsepower for the load with a thermal efficiency of 18.2 per cent. The air enters the intake duct at 80° F. and 14.1 pounds per square inch absolute (p. s. i. a.), assuming an altitude of 1000 ft., and suffers a pressure drop of 0.2 p. s. i. a. in passing through the air washer and intake duct, reaching the compressor at 80° F. and 13.9 p. s. i. a. The axial-flow compressor having an efficiency of 86 per cent raises the pressure to 76.5 p. s. i. a. and the temperature to 470° F., absorbing 12,050 horsepower and putting 30.73 million B. t. u. per hour into the 11,192 moles of air.

The air flows to the combustor where it meets the fuel, which may be natural gas or other suitable fuel. Taking the fuel as being methane, the fuel flow rate is 3,984 pounds per hour, or 249

moles per hour, which is equivalent to 35.95 million B. t. u. (lower heating value) per hour. The combustion is not perfect, and there is some heat lost to the surroundings, so that the enthalpy increase is only 83.45 million B. t. u. per hour, and the hot gases reach the turbine at 1400° F. and 71.8 p. s. i. a., the pressure loss through the combustor and connections being 4.7 p. s. i. a.

In passing through the turbine, the pressure falls to 14.2 p. s. i. a., and the temperature to 868° F., the efficiency of the turbine being 85 per cent. The enthalpy drop is 48.11 million B. t. u. per hour, of which 1.73 million B. t. u. per hour are lost to the surroundings, including direct loss and friction in the turbine and compressor. The balance, 46.38 million B. t. u. per hour, is converted into used mechanical energy; this is 18,190 horsepower, of which the compressor takes 12,050 to return to the air, while 6,140 horsepower remains for the load.

The thermal efficiency is 18.2 per cent; the combustor loss is 2.9 per cent, and the losses in turbine and compressor total 2.0 per cent, while 76.9 per cent of the heat of the fuel remains as sensible heat in the gases which leave the turbine at 868° F. and 14.1 p. s. i. a., the pressure drop through the exhaust duct being 0.1 p. s. i. a.

Some of the heat in the exhaust gases may be used in various ways, as for heating water or generating low-pressure steam; a part may be returned to the cycle by means of an indirect heat exchanger, or regenerator, having two flow paths separated by a diaphragm, one path being inserted between the turbine exhaust and the stack, and the other path between the compressor discharge and the combustor.

The fraction of the heat in the exhaust gases which can be returned to the cycle by means of a regenerator depends upon the temperature at which the gases leave the turbine, the temperature at which the air leaves the compressor, and the number of square feet of heat transfer surface in the regenerator. With a regenerator having 50,000 square feet of heat transfer surface added to the equipment described above, sufficient heat can be transferred from the exhaust gases to the air to raise the thermal efficiency to 25.0 per cent, but only at the expense of a substantial decrease in power output, from 6140 horsepower to 5550 horsepower.

The decrease in power output is caused chiefly by the added pressure drops which come with the insertion of the regenerator. The added pressure drop between the compressor and the combustor acts to decrease the pressure at the tur-

bine inlet from 71.8 p. s. i. a. to 70.5 p. s. i. a., while the added pressure drop between the turbine exhaust and the stack acts to increase the pressure at the turbine exhaust from 14.2 p. s. i. a. to 14.6 p. s. i. a. Thus the entropy rise due to the pressure drop, which is proportional to the logarithm of the ratio of inlet pressure to exhaust pressure, is made less, and the corresponding enthalpy decrease is made less also. In this case the temperature at the turbine exhaust becomes 880° F. rather than 868° F., which decreases the turbine's used power output from 18,190 horsepower to 17,600; since the air flow rate and the pressure at the compressor discharge is not changed, the power taken by the compressor is not changed either, so that all of the decrease in turbine output is suffered by the load.

The fuel rate is decreased from 85.95 million B. t. u. per hour to 56.61 million B. t. u. per hour, or from 249 to 164 moles of methane per hour. The decrease in total moles through the turbine from 11,441 to 11,356 is partially responsible for the decrease in power output, but the principal cause is the decrease in the ratio of inlet pressure to exhaust pressure.

The regenerator adds about 20 per cent to the cost of the gas turbine and reduces its power output about 10 per cent, so that the increase in thermal efficiency from 18.2 per cent to 25.0 per cent is accomplished at the expense of an increase of about one-third in cost per horsepower of output.

By increasing the temperature of the gases at the turbine inlet both power output and thermal efficiency can be increased. However, at the present time the practical maximum temperature is 1500° F., this limit being imposed by materials of construction, particularly for the turbine rotor.

With the turbine inlet temperature limited to 1500° F., increased thermal efficiency can be obtained by increasing the complexity and cost of the apparatus.

In one such suggested method the compression is carried out in two stages, with an intercooler between the two stages. The work of compression is thereby reduced for the same pressure rise, or a greater pressure rise may be obtained with the same work. The heat abstracted by the intercooler cannot in general be recovered, but a large part of it can be replaced by the regenerator, since the temperature of the air leaving the compressor is less than it would otherwise have been, and the lower the temperature of the air leaving the compressor, the greater the quantity of heat which the regenerator can transfer to it.

In a practical operation of such a plural compressor unit, an air flow rate of 72 pounds per second is used to produce 7,130 horsepower for the load with a thermal efficiency of 29.8 per cent. The air enters the intake duct at 80° F. and 13.9 p. s. i. a., the altitude being 1500 feet, and suffers a pressure drop of 0.2 p. s. i. a. in passing through the air washer and intake duct, reaching the first compressor at 80° F. and 13.7 p. s. i. a. The 86 per cent efficient first compressor raises the pressure to 42.3 p. s. i. a. and the temperature to 316° F., absorbing 5800 horsepower and putting 14.78 million B. t. u. per hour into the 8,953 moles of air.

The air then flows through an indirect heat exchanger, or intercooler, where it gives up 13.84 million B. t. u. per hour in cooling to 95° F. The heat is absorbed by water flowing through the intercooler at the rate of 800 gallons per minute

and being heated from 70° F. to 105° F. The intercooler has 21,400 square feet of heat exchange surface.

In passing through the intercooler and ducts the air suffers a pressure drop of 1.4 p. s. i. a., and enters the second compressor at 40.9 p. s. i. a. and 95° F. The 86 per cent efficient second compressor raises the pressure to 131.3 p. s. i. a. and the temperature to 347° F., absorbing 6180 horsepower and putting 15.77 million B. t. u. per hour into the air.

From the second compressor the air flows through the regenerator to the combustor. The regenerator, which has 26,200 square feet of heat exchange surface, puts 22.23 million B. t. u. per hour into the air raising its temperature to 690° F. In the combustor the air meets fuel, supplied at the rate of 61.09 million B. t. u. (lower heating value) per hour, or 177 moles of methane per hour. There is a loss of 1.60 million B. t. u. per hour in the combustor, and a pressure drop of 11.2 p. s. i. a. through the regenerator, the ducts, and the combustor, so the gases at the rate of 9,130 moles per hour reach the turbine at 1500° F. and 120.1 p. s. i. a.

In passing through the turbine the pressure falls to 14.4 p. s. i. a. and the temperature to 850° F., the efficiency of the turbine being 85 per cent. The enthalpy drop is 50.24 million B. t. u. per hour, of which 1.51 million B. t. u. per hour are lost, and 48.73 million B. t. u. per hour are converted to used mechanical energy; this is 19,110 horsepower, of which the compressors take 11,980 to return to the air, leaving 7130 horsepower for the load.

From the turbine the gases pass through the regenerator and the exhaust duct to the stack, which they reach with a temperature of 475° F. and a pressure of 13.9 p. s. i. a., having given up 22.23 million B. t. u. per hour to the air passing to the combustor, and still carrying 25.83 million B. t. u. per hour.

Thus the total heat of 61.09 million B. t. u. per hour supplied as fuel is accounted for as follows: 18.18 million or 29.8% to the load; 25.83 million to the stack; 13.84 to the cooling water; 1.60 lost by the combustor; 1.51 lost by the turbine and compressor, and 0.13 lost by the regenerator and ducts.

By adding a second intercooler, a third compressor, a second combustor and a second turbine the power output per pound of air handled and the thermal efficiency can be further increased. Such plural compressor plural combustor cycle produces 13,240 horsepower with a flow rate of 72 pounds of air per second at a thermal efficiency of 35.3 per cent. The second intercooler, like the first, has 21,400 square feet of surface, and it cools the air from 347° F. to 98° F., removing 15.59 million B. t. u. per hour from the air and heating 780 gallons of water per minute from 70° F. to 110° F. In passing through the second intercooler and the ducts the pressure drops 4.3 p. s. i. a., so the air enters the third compressor at 127 p. s. i. a. and 98° F. The 86 per cent efficient compressor raises the pressure to 381 p. s. i. a. and the temperature to 336° F., absorbing 5850 horsepower and putting 14.92 million B. t. u. per hour into the air.

From the third compressor the air flows through the regenerator to the first combustor. The regenerator, which has 39,300 square feet of heat transfer surface, puts 37.58 million B. t. u. per hour into the air, raising its temperature to 906° F. Burning of 132 moles of methane per

hour in the first combustor supplies 45.55 million B. t. u. per hour, of which 1.64 million B. t. u. per hour are lost, so that the gases enter the first turbine at 1500° F.; the pressure drop through regenerator, ducts, and combustor is 32.4 p. s. i. a., so that the pressure at the inlet to the first turbine is 348.6 p. s. i. a.

The gases expand through the first turbine to 51.6 p. s. i. a.; the turbine efficiency being 85 per cent, the temperature of the gases leaving is 861° F. The enthalpy drop is 45.79 million B. t. u. per hour, of which 1.38 million B. t. u. per hour are lost, leaving 44.41 million B. t. u. per hour in the form of used mechanical energy; this is 17,410 horsepower.

From the first turbine the gases pass to the second combustor, where a second portion of fuel is burned at the rate of 145 moles of methane, or 50.05 million B. t. u., per hour. Of this, 1.35 million B. t. u. per hour are lost, so that the gases enter the second turbine at 1500° F. The pressure drop through the second combustor is 3.2 p. s. i. a., so that the pressure at the inlet of the second turbine is 48.4 p. s. i. a.

The gases expand through the second turbine to 14.4 p. s. i. a. The turbine efficiency being 85 per cent, the temperature of the gases leaving the second turbine is 1021° F. The enthalpy drop is 36.05 million B. t. u. per hour, of which 1.22 million B. t. u. per hour are lost, and 34.83 million B. t. u. are converted into used mechanical energy; this is 13,660 horsepower.

Together the two turbines generate 31,070 horsepower, of which the three compressors recycle 17,830 horsepower to the air, leaving 13,240 horsepower for the load.

From the second turbine the gases flow through the regenerator to the stack, which they reach with a temperature of 480° F. and a pressure of 13.9 p. s. i. a.

The present invention is based on a novel concept of cooling the gases from the combustion from which numerous advantages derive. In order to clearly explain the invention, typical physical embodiments are illustrated in the accompanying drawings in which:

Fig. 1 is a flow diagram of a simple embodiment of the invention;

Fig. 2 is a flow diagram embodying plural compressors associated with a single combustor and turbine; and

Fig. 3 is a flow diagram embodying plural compressors, plural combustors and plural turbines.

The cycle depicted in Fig. 1 makes possible the production of 12,090 horsepower with a thermal efficiency of 24.8 per cent, using an air flow rate of 90 pounds per second and apparatus comparable in simplicity and cost with the apparatus currently employed.

As shown the compressor 1 and turbine 2 are mounted on the shaft 3 from which load 4 is driven. Air is taken from air supply 5 and is passed through the air washer 6 wherein it is washed with water in the conventional manner and thence to the compressor. Air from the compressor is passed directly to a suitable combustor 7 where it meets the fuel fed to the combustor from fuel supply 8 and also a flow of steam from a steam generator 9. The combustion products cooled by steam acting as a direct coolant are expanded into and drive the turbine 2. The air flow rate is 11,192 moles per hour; the fuel flow rate is 124.25 million B. t. u. (360 moles of methane) per hour and the steam flow rate is 3600 moles (64,800 lbs.) per hour. The combus-

tion loss is 3.19 million B. t. u. per hour so that the mixture of steam and combustion products reaches the inlet of the turbine at 1400° F. The pressure drop through the combustor and connection is 4.7 p. s. i. a. so that the pressure at the turbine inlet is 71.8 p. s. i. a.

The method of forming the mixture of steam and combustion products is not critical. The simplest way, as shown in Fig. 1, is to add the steam from generator 9 to the air at the combustor inlet. Since the fuel is normally burned with a minor portion of the air, and the hot combustion products then mixed with the balance of the air, it is also practical to add the steam to that part of the air which is mixed with the combustion products first formed. In the illustrative embodiment the steam generator is shown as an unfired boiler in which hot water drawn from water heater 10 is vaporized by indirect heat exchange with hot gases from the turbine exhaust passing through coils or tubes 11. Such exhaust gases are further cooled in heater 10 before passage to the stack and as noted serve to preheat water fed to the steam generator.

The total flow of gas through the turbine is 15,152 moles per hour, and the turbine exhaust pressure is 14.6 p. s. i. a. As the turbine efficiency is 85 per cent, the temperature of the exhaust is 89° F.

The enthalpy drop is 63.59 million B. t. u. per hour, of which 2.03 million B. t. u. per hour are lost, and 61.56 million B. t. u. per hour converted to used mechanical energy; this is 24,140 horsepower, of which the compressor takes 12,050, leaving 12,090 horsepower for the load.

As noted, from the turbine, the gases pass through the unfired boiler 9, then through an unfired water heater 10 and the exhaust duct to the stack, which they reach at a temperature of 254° F. and a pressure of 14.1 p. s. i. a.

The unfired boiler 9 generates the 64,800 lb. per hour of steam which flows to the combustor. The steam is generated at 310° F. and a pressure of 77.7 p. s. i. a., so that it may flow to the combustor to which the compressor supplies air at 76.5 p. s. i. a.

The unfired water heater 10 heats from 80° F. to 310° F. the 64,800 lb. per hour of water needed to feed the boiler.

The boiler has 20,800 square feet of heat transfer surface, through which the exhaust gases give up to the water 59.88 million B. t. u. per hour, and they leave the boiler at 389° F.

The water heater has 17,000 square feet of surface, through which the exhaust gases give up to the water 15.03 million B. t. u. per hour.

The water heater 10, the boiler 9 and the exhaust duct lose 0.45 million B. t. u. per hour to the surroundings, so the exhaust gases reach the stack still carrying 19.53 million B. t. u. per hour as sensible heat in addition to 68.17 million B. t. u. per hour in the form of the latent heat at 80° F. of the 3600 moles of steam per hour added to the combustor.

The thermal efficiency is 24.8 per cent, the combustor loss is 2.6 per cent, the losses of turbine and compressor total 1.6 per cent, the losses of boiler and water heater total 0.4 per cent, the sensible heat lost to the stack is 15.7 per cent, and 54.9 per cent of the heat of the fuel is lost as latent heat of the added steam.

It will be appreciated that by adding more heat transfer surfaces, the amount of heat transferred from the exhaust gases can be increased, and the thermal efficiency can be increased corre-

spondingly. The steam may be generated at a higher pressure and temperature, or it may be superheated in an unfired superheater, or the exhaust gases may pass through a regenerator which heats the air from the compressor and then through the unfired boiler. For example, generating the steam at 320° F. instead of 310° F. would increase the thermal efficiency to 25.0 per cent, but would require more heat exchange surface, particularly in the water heater.

Comparing the cycle and apparatus of Fig. 1 with prior installations employing a single compressor with a compressed air preheater, it may be seen that the novel cycle of Fig. 1 produces 117 per cent more power at about the same thermal efficiency with the same air compressor, but passes about 34 per cent more volume through the combustor and turbine, requires the turbine to generate and transmit about 37 per cent more power, and requires about 25 per cent less heat transfer surface. The additional cost considering combustor, turbine, and heat exchange surface is about 20 per cent, so that the cost per horsepower is decreased by more than 40 per cent.

It will be noted that the boiler 9 and water heater 10 of Fig. 1 have each but one path in the gas circuit. Thus the boiler and water heater can be designed for low pressure drop in the gas circuit and high pressure drop in the water-steam circuit; this improves the power output of the turbine with but a small additional load on the feed water pump, which in any event takes only a few horsepower. It will be noted also that as compared to prior installations where the maximum temperature of the heat transfer surface in the regenerator is comparable to the temperature at which the gases leave the turbine, in the novel system of the invention the maximum temperature of the heat transfer surface in the boiler 9 is not much greater than the temperature of the boiling fluid. By reason of the high allowable pressure drop in the water-steam flow path and the lower maximum temperature, the cost of the boiler and water heater, per square foot of surface, can be substantially less than that of the regenerators used in prior art systems.

The division of the compressor into two or more stages, with intercooling between the stages and the division of the turbine into stages of expansion, with reheat between stages, can be employed to improve thermal efficiency. It has been found desirable, particularly in connection with the improved cycle, to use adiabatic cooling between compressor stages, the cooling being accomplished by the injection of liquid water which vaporizes.

The first of these improvements is illustrated by the flow diagram of Fig. 2. As there shown the system comprises the first compressors 21 and second compressor 22 mounted on the shaft 23. The turbine 24 similarly is mounted on shaft 22 and drives the two compressors and load 25. As in the first described embodiment, air is taken from an air supply 26 and is passed through the air washer 27 and thence to the first compressor 21. Air compressed in the first compressor as shown is passed through the adiabatic cooler and thence through the second compressor 22 to the combustor 29. The cooler 28 preferably is a spray chamber type; this is much less costly than an indirect cooler and imposes a much smaller pressure drop than an indirect cooler although it may not be quite so effective in reducing the work of the compressor 22.

As in the embodiment illustrated in Fig. 1,

steam is generated in a steam generator, such as the unfired boiler 30, by vaporizing preheated water by indirect heat exchange with hot exhaust gases from the turbine. These gases thus pass to the water heater 31 to preheat the water supplied to steam generator and are discharged to the stack.

In the combustor the air from the second compressor in admixture with steam from generator 30 meets the stream of fuel from fuel supply 32 and the products of combustion are expanded in the turbine 24.

In such a cycle the air flow rate to the compressor is 72 lbs. per second. The cooler 28 is designed to introduce 466 moles of water per hour, and the mixture of air and water vapor enters the second compressor at 170° F. and 41.7 p. s. i. a. The second compressor raises the pressure to 133.8 p. s. i. a. and the temperature to 456° F. absorbing 7530 horsepower and introducing 19.31 million B. t. u. per hour into the air and steam.

In the combustor the air-steam mixture from compressor 22 meets fuel flowing at the rate of 109.2 million B. t. u. (317 moles of methane) per hour, and steam from generator 30 flowing at the rate of 2334 moles per hour. There is a loss of 2.72 million B. t. u. per hour, and the mixture of combustion products and added steam enter the turbine 24 at 1500° F. The pressure drop in the combustor and connections is 8.4 p. s. i. a., so that the pressure at the turbine inlet is 125.4 p. s. i. a.

The total flow through the turbine is 12,070 moles per hour, and the turbine exhaust pressure is 14.4 p. s. i. a.; the turbine efficiency being 85 per cent, the turbine exhaust temperature is 822° F.

The enthalpy drop is 68.35 million B. t. u. per hour, of which 1.88 million B. t. u. per hour are lost, the remaining 66.47 million B. t. u. per hour being converted into used mechanical energy; this is 26,070 horsepower, of which the two compressors take 13,350 horsepower to return to the air, while 12,740 horsepower remain for the load. Thus the thermal efficiency is 29.7 percent.

From the turbine the gases pass, as explained, through the unfired boiler 39 having 17,200 square feet of heat exchange surface, the unfired water heater 31 having 12,000 square feet of heat exchange surface, and the exhaust duct to the stack, which they reach at a pressure of 13.9 p. s. i. a. and a temperature of 293° F.

The boiler 30 generates at 350° F. and 134.6 p. s. i. a. the 2334 moles of steam per hour which are added to the circuit at the combustor, using 38.07 million B. t. u. per hour and cooling the gases from 822° F. to 420° F. The water heater provides the boiler feed, heating 2334 moles of water per hour from 80° F. to 350° F., and using 11.43 million B. t. u. per hour.

Comparing the cycle of Fig. 2 with the plural compressor and intercooler systems of the prior art, the improved cycle produces about 78 per cent more power at about the same air rate, using a second stage compressor which requires about 22 per cent more power because it handles about 5 per cent more moles taken in at about 14 per cent higher absolute temperature, a combustor and a turbine which handle about 32 per cent more moles, a turbine which generates and transmits about 37 per cent more power and an additional spray chamber, but using about 38 per cent less heat exchange surface. The additional cost of making the second compressor, combustor

and turbine slightly larger about balances the saving on heat exchange equipment, so that the cost per horsepower should be decreased more than 40 per cent.

A further modification of the invention which is shown diagrammatically in Fig. 3 involves the use of multiple stages of compressors and turbines with reheating of the gas between the two turbine or expansion stages. As shown in Fig. 3 the compression is divided into three stages comprising the compressors 41, 42 and 43, each mounted on the shaft 44 which shaft is driven by the turbines 45 and 46. Power is transmitted from the turbine to shaft 44 to drive the compressors and also the load 47. As compared with prior art installations using an equivalent combination of plural compressors and turbines, but without utilizing the novel cooling concept of the invention, the installation depicted in Fig. 3 produces 109 per cent more power with about the same thermal efficiency.

This modification, as indicated in the drawings, utilizes intercooling between the sequential compression stages and reheating between the expansion stages. The operation will have been appreciated from the earlier discussion of the first two modifications. Air from air supply 48 is washed in washer 49 and is passed to the first compressor 41. Compressed air from compressor 41 is then cooled in the adiabatic cooler 50 and is passed sequentially through the second compressor 42 and cooler 51 to the third compressor 43. The mixture of compressed air and water vapor from compressor 43 as shown is continuously charged to the first combustor 52.

As in the previously described drawing, steam is admitted to the combustion zone to effect the desired cooling of the combustion gases. Such steam is formed in a suitable steam generator such as the unfired boiler 53, the heat for this generator being supplied as shown, by indirect heat exchange with hot gases from the second turbine 46. These exhaust gases are further cooled in the water heater 54 while preheating the water fed to boiler 53.

In the first combustor 52 the mixture of air and steam meets the fuel fed from fuel supply 55 and the products of combustion as shown are expanded in turbine 45. From the first turbine the expanded gases pass to the second combustor 56 fed with fuel from supply 55 and the products of combustion are expanded in the second turbine 46. The turbine exhaust as noted is utilized to generate steam and preheat the water supply to the steam generator thus most effectively lowering the stack temperature of the exhaust gases.

This installation employs 72 pounds of air per second to produce 27,710 horsepower with 35.6 per cent thermal efficiency to produce, as previously noted, 109 per cent more power with about the same thermal efficiency as presently utilized installations of the equivalent plural compression and turbine stages.

Compressors 41 and 42 and the first intercooler 50 are identical with those previously described in Fig. 2; similarly the inlet air conditions and the conditions at the discharge of second compressor 42 are identical with those of Fig. 2. The second adiabatic cooler 51 introduces 650 moles of water vapor per hour into the circuit concomitantly reducing the temperature to 260° F. This second intercooler and connections consume 1.8 p. s. i. a. and the gases enter the third compressor at 132 p. s. i. a. The third compres-

sor raises the pressure to 396 p. s. i. a. and the temperature to 553° F. absorbing 8430 horsepower and putting 21.51 million B. t. u. into the mixture of air and steam.

5 The mixture of steam and air passes from the compressor 43 to the combustor 52 and is admixed with fuel introduced at the rate of 124.25 million B. t. u. (360 moles of methane) per hour and steam entering from generator 53 at the rate of 4000 moles per hour. The thermal loss in combustor 52 is 3.13 million B. t. u. per hour, and the mixture of combustion products and steam enters turbine 45 at 1500° F. During passage through the combustor 52 and its connections, the pressure drop is 25 p. s. i. a. and hence the pressure at the inlet of turbine 45 is 371 p. s. i. a. The gases expand in turbine 45 down to 69.5 p. s. i. a.; the turbine efficiency being 85 per cent, the temperature of the gases exhausted from turbine 45 is 962° F.

In the second combustor 56 fuel is added at the rate of 73.75 million B. t. u. (214 moles of methane) per hour. The loss in the second combustor is 2.16 million B. t. u. per hour and the gases enter the second turbine at 1500° F. The pressure drop through the second combustor and connections is 5.4 p. s. i. a. and thus the pressure of the gases at the inlet to the second turbine is 64.1 p. s. i. a.

25 The gases expand in turbine 46 down to 14.4 p. s. i. a.; with the turbine efficiency 85 per cent, the temperature of the exhaust gases from turbine 46 is 1021° F.

The enthalpy drop in the turbine 45 is 67.45 million B. t. u. per hour, of which 1.85 million B. t. u. per hour are lost; the enthalpy drop in turbine 46 is 62.32 million B. t. u. per hour, of which 1.76 million B. t. u. per hour are lost; thus the two turbines convert into used mechanical energy 126.16 million B. t. u. per hour, which is 49,470 horsepower. The three compressors recycle 21,760 horsepower to the air, leaving 27,710 horsepower for the load, so that the thermal efficiency is 35.6 per cent.

40 From turbine 46, as noted, the gases flow through the unfired boiler 53, which has 26,700 square feet of heat exchange surface, and generates at 400 p. s. i. a. and 445° F. the 72,000 pounds of steam per hour added at the first combustor, and transfers 60.61 million B. t. u. per hour from the gases to the boiling liquid while cooling the gases to 508° F.

45 From the unfired boiler the gases flow through the unfired water heater 54 and exhaust duct to the stack. The water heater has 32,500 square feet of heat exchange surface, and it heats from 80° F. to 445° F. the 72,000 pounds of water per hour which the boiler converts to steam, putting 27.07 million B. t. u. per hour into the water and cooling the gases to 260° F.

50 In passing through the boiler, water heater and exhaust duct the gases suffer a pressure drop of 0.5 p. s. i. a., and reach the stack at 13.9 p. s. i. a.

55 To produce 109 per cent more power than the comparable prior art multiple compressor-multiple turbine units with the same air flow rate and the same thermal efficiency, the cycle depicted in Fig. 3 requires 22 per cent more compressor horsepower, combustors and turbines which handle 59 per cent more moles of gas, and a turbine which generates and transmits 59 per cent more power, and two adiabatic intercoolers; but it requires 38 per cent less heat exchange surface, and none of the heat exchange surface

has to operate at high temperature in the cycle of Fig. 3, while part of the heat exchange surface in the comparable prior art cycle must operate at temperatures which are high for ordinary steel.

It will be appreciated that various mechanical modifications may be made without departing from the spirit of the invention. For example, each turbine may be divided into two parts, each with its own shaft, in series, and these may operate at different speeds; or the stream of gas passing to a combustor may be split into two or more streams, each of which may then pass to a separate combustor and turbine. Also, while, as described, it is preferred to mix the added steam with the combustion products before the turbine inlet, it may be arranged that combustion products are supplied to some of the turbine nozzles and steam to the others, so that the mixing takes place in the turbine.

The usual methods of controlling the speed and load may be used with the apparatus of this invention, but in addition the quantity of steam added may be decreased at part load; when the quantity of steam added is decreased, the pressure and temperature at which the steam is added may be increased, thereby improving the thermal efficiency at part load.

The water used in the adiabatic intercoolers is preferably free from non-volatile matter; however, in some cases water containing non-volatiles in solution may be used, provided an excess of water is introduced, and the unevaporated excess is allowed to flow to waste carrying the non-volatiles away with it. For marine application the boiler may be fed with sea water, in which case there must be sufficient excess feed to carry away the non-volatiles.

The heat remaining in the gases leaving the water heater may be used for heating water, or for comfort heating, or for preparing distilled water in evaporators, which distilled water may then be used for the adiabatic coolers or the boiler.

The applications of the invention described above have been for power outputs of thousands of horsepower. The invention may also be used for lower power outputs, with proportionately greater benefits. The axial-flow compressor is not so suitable for low flow rates, such as would be needed for a power output of less than one thousand horsepower, as is the centrifugal compressor, but the efficiency of the centrifugal compressor is substantially lower. Since in the improved process of the present invention the power taken by the compressor is only about half of that generated by the turbine when the efficiency of the compressor is 86 per cent, whereas in the conventional gas turbine the 86 per cent efficient compressor takes about two thirds of the generated power, the present invention makes it practical to operate with a compressor having only 60 per cent efficiency. Thus the internal combustion turbine is made practical for power outputs of the order of 200 horsepower, with a thermal efficiency of 15 per cent.

The improvements obtained by the present invention require for full exploitation the use of about 10 pounds of water per pound of fuel, which could be a limiting feature in some cases where water is scarce or for mobile applications where the water must be carried. In such cases partial advantage may be obtained by using a smaller quantity of water.

It is particularly to be observed that the funda-

mental concept of the invention is the use of steam as a coolant and the generation of at least part of the steam with heat which could not otherwise be made available for conversion into mechanical energy anyway. In the earlier period of the development of the gas turbine many suggestions were advanced as to driving the turbine by a mixture of gas and steam. These suggestions were advanced at a time when the gas turbine then known had difficulty driving its own compressor. In the modern successful gas turbine the criteria are maximum simplicity in design and maximum reliability in operation.

While the conversion of water into steam under pressure has the advantage that it requires no mechanical energy, except for the little demanded for the feed water pump, this must be paid for with latent heat and a steam power plant cannot work at high thermal efficiency except by operating at high pressure. On the other hand, the modern successful gas turbine operates at moderate pressure and high temperature. Hence, in the past, substituting steam for air as a cooling medium could only be justified when the thermal efficiency of the gas turbine which used the steam was less than about 12 per cent.

Using the heat in the exhaust gas from the turbine to generate the steam improves the efficiency, to be sure, but the heat in the exhaust gas can also be used to preheat the air. It makes no difference from the fuel consumption standpoint whether fuel is burned to generate steam in the combustion chamber to mix with air preheated by the exhaust gases, or fuel is burned in the combustion chamber to heat cold air which is then mixed with steam generated by heat abstracted from the exhaust gases—provided the amount of heat recycled from the exhaust gases is the same in both cases. But the amount of heat recycled from the exhaust gases need not be the same in the two cases.

If the cost of the equipment were unimportant, the compression of the air could take place at constant temperature, or at least with substantially no increase in temperature, and then the amount of heat transferred from the exhaust gases to the compressed air could be sufficient to increase the temperature of the compressed air almost but not quite up to the temperature at which the exhaust gases leave the turbine; in such a case the temperature of the exhaust gases would be reduced almost to atmospheric.

However, the cost of the equipment is important. It is therefore not economic to attempt to obtain very low final compressor discharge temperature, nor to increase the temperature of the compressed air by transfer from the exhaust gases beyond a temperature still substantially lower than that at which the exhaust leaves the turbine. In the examples given of gas turbine processes which are representative of the present state of the art, the lowest temperature at which the exhaust gases leave the regenerator is 475° F. In this case the amount of heat carried to the stack by the exhaust gases is over 40 per cent of that supplied as fuel. This is heat which theoretically could be recovered, but practically can not be, in the currently employed process.

By the present invention, however, a substantial fraction of this heat can be recovered and put to use in the power generation cycle. This recovered heat may be used to improve the thermal efficiency, or to make up for the loss which takes place when steam is generated by heat which could have been used for heating the

air. In the first described embodiment the objective is lower machine cost with the same thermal efficiency, though the possibility of improved thermal efficiency is mentioned. In the second embodiment the objective is higher thermal efficiency, without excessive machine cost.

While the reduction in cost per horsepower will be less if the quantity of water used is less, there will be possible an offsetting gain in thermal efficiency. This gain in thermal efficiency may be obtained by one or more of the expedients previously mentioned; that is, by generating the steam at a higher temperature and pressure; or by superheating it in an unfired superheater through which the exhaust gases flow to the boiler; or by passing the exhaust gases through a regenerator, which heats the air from the compressor, and then through the boiler.

It will be understood that the ratio of water to air which is to be used in each case is determined by the form in which the benefits of the invention are to be obtained, provided sufficient water is available. With a relatively small ratio of water to air both thermal efficiency and machine cost are improved. As the ratio of water to air is increased, the cost per horsepower decreases more and more, but the thermal efficiency increases to a maximum, and then decreases. In the examples given the water-air ratio has been chosen to obtain low cost per horsepower while keeping the thermal efficiency about the same as in the comparable cycles of the present state of the art. Still lower cost per horsepower may be obtained by employing higher water-air ratios, but the thermal efficiency will be less.

In applying the invention to the improvement of a particular gas turbine cycle, the temperature at which the exhaust gases pass to the stack is an important guide. Thus in the example given in connection with one prior art installation the exhaust gases pass to the stack at a temperature of 868° F. carrying 76.9 per cent of the heat of the fuel, and the thermal efficiency is 18.2 per cent. In the example given in connection with prior methods using preheated air the thermal efficiency is 25.0 per cent, the improvement being due to the regenerator which reduces the temperature of the exhaust gases to 552° F. and returns to the process enough heat to raise the temperature of the air from 470° F. to 800° F. In the example of the invention given in connection with Fig. 1 the thermal efficiency is 24.8 per cent, the improvement over the comparable prior art installation being due to the boiler and water heater which reduce the temperature of the exhaust gases to 254° F. In these examples, therefore, the use of the present invention to obtain a large decrease in cost per horsepower with about the same thermal efficiency employs such a water-air ratio as to decrease the exhaust gas temperature to 254° F. in comparison to the decrease in exhaust gas temperature to 552° F. which takes place when a regenerator is used.

It will be noted that in the representative prior method using multiple compressors with regenerative heating of air the exhaust gases pass to the stack at 475° F. while in the comparable cycle of the invention shown in Fig. 2 the exhaust gases pass to the stack at 293° F.; also, that in the prior art using multiple compressors and multiple turbines the exhaust gases pass to the stack at 480° F. while in the com-

parable cycle of Fig. 3 the exhaust gases pass to the stack at 260° F. Thus in all examples the present invention is applied to bring the temperature of the exhaust gases to a value substantially lower than regenerators could, but still substantially higher than atmospheric.

While a larger regenerator would allow more heat to be recovered, it is not possible in any case for a regenerator to reduce the temperature of the exhaust gases below the temperature at which the air leaves the compressor, this temperature being as high as 470° F. in these examples, while by using a large water-air ratio the temperature of the exhaust gases can be brought close to atmospheric, thereby decreasing the sensible heat loss. While the power output increases with the water-air ratio, the latent heat loss increases also. It is therefore an important feature of the invention to employ such a water-air ratio and so much heat transfer surface in each case as to obtain the desired balance between thermal efficiency and cost of equipment, controlling the thermal efficiency by the balance between latent heat loss and sensible heat loss and the equipment cost by the balance between heat transfer surface cost and rotating equipment cost. The heat transfer surface may be distributed among water heater, boiler, superheater, and regenerator, depending upon the water-air ratio employed and the relative cost of the various forms.

While preferred embodiments of the invention have been described, it is to be understood that these are given to illustrate the underlying principles of the invention and not as limiting its useful scope except as such limitations are imposed by the appended claims.

I claim:

1. A power production process comprising the steps of generating steam from liquid water; compressing atmospheric air to a temperature substantially superatmospheric; passing the compressed air to a zone where fuel is introduced and combustion takes place continuously, but without increase of pressure; passing the combustion products and excess air in admixture with the steam continuously through an expansion zone where mechanical energy is abstracted, in amount substantially greater than the mechanical energy absorbed in the compression step; and passing the expanded mixture in indirect heat exchange relationship with the water to generate the steam, the pressure at which the steam is generated being not less than the pressure at the entrance to the expansion zone, and the quantity of heat abstracted from the expanded mixture for recycling to the expansion zone being large enough to reduce the temperature of the expanded mixture to a value not substantially greater than the temperature of the air at the end of the compression step whereby the heat absorbed as latent heat in the steam generation step is supplied by abstraction of sensible heat from said expanded mixture without requiring the combustion of additional fuel to supply such latent heat.

2. The process of claim 1 wherein the steam is superheated by heat abstracted from the expanded mixture, and the expanded mixture passes in indirect heat exchange relation with the steam through the steam superheating zone before said mixture enters the steam generation zone.

3. The process of claim 1 wherein the water is

heated to the saturation temperature from a temperature substantially lower by means of heat abstracted from the expanded mixture whereby the temperature of the expanded mixture is reduced to a value substantially lower than the temperature of the air at the end of the compression step.

4. The process of claim 1 wherein the pressure at which the steam is generated is made substantially higher than the pressure at the entrance to the expansion zone, whereby the water-air ratio is controlled to increase the thermal efficiency.

5. The process of claim 1, wherein are comprised the steps of compressing the air in a plurality of stages and expansion takes place in a series of zones through which combustion products pass sequentially of transferring at least a substantial portion of the heat removed from the compressed air during the cooling between stages and at least a substantial portion of the sensible heat of the gases after the abstraction of mechanical energy therefrom to water to generate steam therefrom at substantially superatmospheric pressure, and adding said steam to the mixture of combustion products and excess air before the expansion.

6. The process of claim 5 wherein there are employed a plurality of combustion zones, arranged sequentially, in each of which fuel is introduced, with an expansion zone between two consecutive combustion zones, and an expansion zone after the last combustion zone in the flow path.

7. The process of claim 5 wherein the expansion zone in which the steam is admixed with combustion products is not the first in the series.

8. The process of claim 1 wherein the quantity of steam admixed with the combustion products and excess air is decreased as the power required is decreased.

9. The process of claim 8 wherein the temperature of the steam before admixture is increased as the power required is decreased.

10. A power production process comprising the steps of continuously generating saturated steam from liquid water; compressing air to a temperature substantially superatmospheric; continuously passing the compressed air to a zone where fuel is introduced and combustion takes place continuously, but without increase of pressure, the rate of fuel introduction being so selected with respect to the rate at which compressed air enters said combustion zone that the ratio of air to fuel in the feed to the combustion zone is substantially greater than stoichiometric; continuously passing the combustion products and excess air in admixture with the steam through an expansion zone where mechanical energy is abstracted, in amount substantially greater than the mechanical energy absorbed in the compression step; and passing the expanded mixture in indirect heat exchange relationship with the water to generate the steam, the pressure at which the steam is generated being not less than the pressure at the entrance to the expansion zone, whereby the heat absorbed as latent heat in the steam generation step is supplied by abstraction of sensible heat from said expanded mixture without requiring the combustion of additional fuel to supply such latent heat.
